UNITED STATES PATENT OFFICE

JOSEPH A. WADDELL, OF WILLIAMSPORT, PENNSYLVANIA, ASSIGNOR TO SPENCER HEATER COMPANY, OF WILLIAMSPORT, PENNSYLVANIA, A CORPORATION OF PENNSYLVANIA

SECTIONAL HEATER

Application filed August 6, 1930. Serial No. 473,431.

- This invention relates to sectional boilers and has for its object to provide a construction which is simple in parts, and more efficient in use than those heretofore proposed. 5 With these and other objects in view the invention resides in the novel details of construction and combinations of parts as will be disclosed more fully hereinafter and particularly pointed out in the claims. 10 Referring to the accompanying drawings forming a part of this specification and in which like numerals designate like parts in all the views,

Fig. 1 is a perspective view of a boiler made 15 in accordance with this invention, the front section having been removed to more fully illustrate the interior construction and arrangement of parts;

Fig. 2 is a partial sectional view of the 20 bottom or throat portion of the fuel magazine;

Fig. 3 is a central longitudinal vertical 25 sectional view of the complete boiler; and

Fig. 4 is a partial diagrammatic view illustrating the use of the boiler with only one 30 grate in operation.

Sectional boilers have been produced heretofore, and of the fuel magazine type, wherein the magazine has been disposed centrally 35 of the boiler so that the fuel will feed by gravity onto a double grate, and boilers employing a single grate have been devised with a magazine located on one side of the boiler so that the fuel will feed by gravity in a downward and inclined direction over said 40 grate.

The boiler of this invention is designed to combine both of these features namely, the provision of a double grate as well as duplicate fuel magazines which latter are disposed on opposite sides of the boiler.

Referring to the drawings, and particularly Fig. 3 thereof, there is shown a front section generally indicated by the numeral 1, a rear section indicated by the numeral 2, and a plurality of identical intermediate sections indicated at 3, each section being provided with ribs 4, which are ground to provide close contacting edges between the adjacent sections, as well as nipples generally indicated

at 5 closely interfitting to provide passages between the sections for water or steam. There are preferably provided three nipples on each section, one located centrally at the top thereof, and one disposed approximately 55 at the upper extremity of the grate in each water leg at the sides of the boiler sections. Each intermediate section is provided with a hollowed portion on one side constituting a water leg 6 which is in open communication 60 at its bottom with the water passage 7 about which is disposed one of the nipples 5, said water leg at its top being in open communication with a hollowed portion constituting a cross chamber 8 leading to the other side 65 of the section where it is in open communication with the top of a water leg 9 similar in every respect to the water leg 6, the water leg 9 at its bottom being in open communication with the water passage 10 having thereabout another of the nipples 5 for joining the sections together. Each section below the water passages 7 and 10 is provided with a leg portion 11 by means of which the section 70 is supported on the floor.

The cross chamber 8 at the top of the boiler section communicates with a plurality of vertical spaced downwardly extending water passages 12 which terminate in a slightly arched water conduit 13 which in turn communicates with a plurality of vertical spaced downwardly extending water passages 14 leading to a lower slightly arched water conduit 15 the outer ends of which are downwardly extended as indicated at 16 and directed obliquely toward the side water legs hereinbefore mentioned. On each side of each section is a water conduit 17 extending obliquely upwardly toward the center of the boiler and joining each water leg with the water conduit 15, see Figure 1. The water conduits 13 and 15, as well as the cross chamber 8 and the water legs 6 and 9, are substantially of a width equal to the thickness of the of the section, but the passages 12, 14, 16 and 17 are slightly less in thickness than the said section, whereby there are created air spaces in and around each of the latter. All of the water passages and conduits are somewhat 80 oval or rounded so that the gases of combus- 85

tion, as well as the fuel may pass around the outer surfaces thereof.

The rib 4 hereinbefore mentioned extends from a lower nipple 5 upwardly, across the top, and downwardly on the other side of the section to the other nipple in substantially the outer plane of the boiler section, and a rib 20 extends from each lower nipple 5 upwardly along the inner edge surface of the water leg to join the aforementioned rib 4 at a point well above the bottom of the fuel magazine, as indicated at 21.

The water passages 12 are formed as a central group to provide on either side thereof of a fuel magazine indicated at 22, said magazine being formed by the cross chamber 8 at the top, the water conduit 17 at the bottom, the water leg such as 6 on the outer side of the boiler section, and on the inner side by the downwardly extending water passage such as 23 which is the outermost of the passages 12. The water passage 23 is continued downwardly and inclined toward the side of the boiler section to constitute the outer of the passages 14, and terminates in the downwardly extending end 16 of the water conduit 15, all as will be clearly understood from the drawings. A rib 24 extends from the rib 4 downwardly along the outer portion of the passage 23 but terminates at the bottom of the portion 16. A similar rib 25 is symmetrically disposed on the other side of the boiler section, and between the ribs 24 and 25 along each of the conduits 13 and 15 are provided ribs 26 and 27 respectively. Lastly, a rib 28 is disposed on the water leg 9 which rib is symmetrical in every respect with the above described rib 20.

It this results that when the sections are correctly secured together by tie rods, not shown but readily understood, all of the aforementioned ribs will contactingly abut with similar ground ribs on the adjacent sections as a result of which the boiler as a whole will be made tight. Further, the ribs 4, 20 and 24 will close off one fuel chamber from the rest of the boiler except at the magazine throat immediately above the grate, and in like manner the ribs 4, 25 and 28 will close off a similar fuel chamber on the other side of the boiler which is only open at the magazine throat immediately above the other grate. Also the ribs 4, 24, 25 and 26 will form a flue chamber at the top of the boiler completely closed off from the fuel magazine chambers, and the ribs 24, 25, 26 and 27 will form a second closed flue chamber immediately below the first mentioned flue chamber, it being understood that the water passages 12 and 14 are disposed in spaced relation whereby the flue gases may pass therearound.

The front section 1 comprises a large water jacket 30 with an opening therethrough in registry with each fuel magazine chamber

22, each of which openings is closed by a door. Between the two magazine openings is another opening 31 closed by the door 32 which opening provides means for cleaning the flue chamber passages around the water tubes 12 and 14. Immediately below the opening 31 is another opening 33, closed by the door 34, which communicates with the fire pot or combustion chamber generally indicated by the numeral 35. Lastly, on each side of the lower front section are other openings each closed as by a door 36 which give access to the ash pits such as 37 and 38. The water jacket of the front section extends thereacross and around the aforementioned openings, with the exception of the ash pit openings, and said water jacket communicates with the next adjacent intermediate section 3 by means of the water passages 7 and 10 in the legs, and the water passage 39 at the top of the sections, said jacket terminating at the lower extremities of the grates.

The rear section 2 likewise comprises a water jacket 40 extending thereacross and communicating with its next adjacent intermediate section 3 by said water passages 7, 10 and 39. Centrally of the rear section is the flue opening 41 communicating with the flue chamber associated with the water passages 12, and clean-out openings 42 and 43 communicating respectively with the lower flue chamber associated with the passages 14, and the fire pot 35. The water jacket 40 likewise terminates at its bottom in substantially the lower plane of the grates.

Both the front and rear sections have their outer faces extended downwardly to form the lower front and rear walls 44 and 45 respectively of the ash pit, and closely fitting therebetween is an I-beam or other similar structural member 46 dividing the ash pit into two halves said beam forming the central support for the grates. This I-beam is suitably secured at its ends as by bolts 47 to suitable flanges on the aforementioned walls 44 and 45. On the upper flange of the I-beam is secured a plurality of similarly formed saddles 48 each of a width equal to the thickness of an intermediate section. Each saddle has a sloping upper surface of a formation very similar to a ship roof of a house or building. That is to say, there is a central ridge from which the upper surface such as 49 slopes slightly downwardly to points substantially above the edges of the upper flange of the I-beam, and then said surface on each side slopes more sharply downwardly as indicated at 50 terminating just below the horizontal plane of said flange. This last mentioned slope 50 is parallel to the surface 51 formed on the inner side of the water leg just below the lower water passage 10. The surface 50 of each saddle has secured thereto a lug 52, and the surface 51 has formed in the upper portion thereof a groove 53, said lug and said

groove adapted to receive opposite ends of the rod for the grate section 54.

It will thus be understood from the foregoing that there is a saddle for each intermediate section and that there is a grate such as 54 between said saddle and said section, the side edges of the grate being serrated or toothed to intermesh with the edges of the next adjacent grate. Also, the inner surface 10 of the front and rear sections is provided with a sloped extension indicated at 55 which has a serrated edge for intermeshing engagement with the adjacent grate sections. It should further be understood that each saddle 15 48 is disposed below the horizontal plane of the water passages 7 and 10 as a result of which the grate section 54 will be inclined with its highest point next the water leg, whereby fuel from the magazine 22 will pass, 20 under the urge of gravity, downwardly through the spaces 56 (see Figure 2) between the water conduits 17 and drop onto the highest portion of the grate from which said fuel will slide over the downwardly inclined grate 25 surface toward the saddles 48 located at the longitudinal center of the boiler (see Figure 4). Each grate section 54 is preferably made in two parts with a shaker bar such as 57 connected to each and extending forwardly 30 through the front section 1 to a bell crank such as 58 to which may be applied a suitable shaking lever. The other side of the heater is provided with a grate section such as 60 which is a duplicate of the grate section 54 35 and mounted in a similar manner so that fuel from the other magazine may pass in a similar manner to meet, at the longitudinal center of the heater, the fuel from the first mentioned magazine.

40 With particular reference to Fig. 3 it will be seen that the gases of combustion will pass from the fire pot 35 in the direction of the arrows, toward the rear section 2 thence upwardly around the rearmost water conduit 45 15, thence forwardly through the lower flue chamber between the water conduits 13 and 15 to the front section 1, thence upwardly around the front conduit 3 into the upper flue chamber and thence in a rearward direction 50 between the top cross chambers and the conduits 13 to and through the flue opening 41, the several ribs 26 and 27 preventing any vertical flow of said gases between the conduits 13 and 15. It will further be understood 55 that the water in the conduits 15 and their downwardly extending portions 16 will receive the highest temperature of the gases of combustion so that circulation of the water is effected from the lower portions of the 60 water legs through the passages 17 to the passages 23, and from the conduits 15 upwardly through the passages 14 through the conduits 13 and passages 12 to the cross chambers 8 at the top of the heater, the return circuit 65 of the water being in directions from the

longitudinal center of the boiler laterally in said cross chambers 8 to the sides of the boiler and thence downwardly through the passages 6 and 9 to the lower portion of the water legs. A suitable water inlet 61 is provided 70 at a low elevation in the rear section 2, and a water outlet 62 is provided at the top portion thereof as will be readily understood.

From the foregoing it will readily be understood that fuel from the two magazines 22 75 will pass downwardly through the throat formed by the choke water passages 16 to the plural grates and that drafts may be regulated through the ash pits 37 and 38 to control the amount of combustion, as a result of 80 which maximum heating effect of the boiler is obtained. This boiler is especially designed for larger buildings and, to operate both grates thereof during the spring and fall months, when less heat is required, would cause an unnecessary and wasteful consumption 85 of fuel. Therefore the magazines for the fuel have been placed on the outer sides of the boiler, and there have been provided two grates supported by an imperforate partition consisting of the I beam 46 which latter forms two separate ash pits. As a consequence, the boiler automatically is divided into two halves, either of which can be independently operated. That is to say, 90 95 either one of the fuel magazines 22 can be charged whereupon the fuel will flow to the grate associated therewith and lie thereover as indicated diagrammatically in Figure 4. The drafts in connection with said grate 100 would be operated as necessary but the other side or half of the boiler would remain inoperative, with its drafts closed, and its magazine and associated grate empty. The result 105 would be that heat from one half of the total grate area would be generated which would in turn heat the water of the entire boiler and generate sufficient steam for heating the building in the spring and fall months. When the weather became colder the other 110 magazine 22 could be filled with fuel and the other side of the heater fired to augment the heating effect, thereby establishing the full 100% operation of the heater.

115 It is obvious that those skilled in the art may vary the details of construction and arrangements of parts without departing from the spirit of the invention, and therefore it is not desired to be limited to the foregoing except as may be required by the claims.

120 What is claimed is:—

1. In a water heater the combination of a plurality of sections placed side by side and so shaped as to form a water-jacketed fuel magazine on opposite sides of the heater, the water-jacket on one side of each magazine extended downwardly to form a water leg, and a combustion chamber below and between said magazines; a grate below each magazine and meeting a water leg at one end; and 125 130

means for supporting the other end of the grates.

2. In a water heater the combination of a plurality of sections placed side by side and so shaped as to form a water-jacketed fuel magazine on opposite sides of the heater, the water-jacket on one side of each magazine extended downwardly to form a water leg, separated flues for the gases of combustion between said magazines, said flues intercepted by water passages, and a combustion chamber below each magazine and communicating with said flues, the bottoms of said magazines formed by spaced water conduits communicating with said water legs as well as with the water passages intercepting said flues; and a grate below each magazine and combustion chamber.
3. In a water heater the combination of a plurality of sections placed side by side and so shaped as to form a water-jacketed fuel magazine on opposite sides of the heater, the water-jacket on one side of each magazine extended downwardly to form a water leg, flues between said magazines, and a combustion chamber below and between said magazines, the bottoms of said magazines formed by spaced water conduits communicating with said water legs as well as with water passages extending across said flues; a grate below each magazine; and means for supporting the grates.

4. In a water heater the combination of a plurality of sections placed side by side and so shaped as to form a water-jacketed fuel magazine on opposite sides of the heater and a combustion chamber below and between said magazines, the water-jacket on one side of each magazine extended downwardly to form a water leg; a grate below each magazine and supported at one end in said water leg; and common means for supporting the other end of the grates.

5. A water heater comprising front, back and intermediate sections, with double grates, independent ash pits, single combustion chamber, and water-jacketed fuel magazines separated by connected flues, the water-jacket on one side of each magazine extended downwardly to form a water leg supporting one end of each grate.

6. In a heater construction of sectional magazine feed type with double inclined grates the combination of a water leg disposed on each side of a section, said legs extending to the top of said section and each provided with an inclined inner surface; a chamber in open communication with said water legs and extending across the top of said section; extensions of said chamber depending therebelow each inclined towards the inclined surface of a water leg to form therewith a constricted throat through which the fuel passes from a magazine therefor; a water conduit in open communication with

and connecting each depending extension with a water leg said conduit extending to a point near the grate, and outlets from said water legs and from said chamber to an adjacent section.

7. In a heater construction of sectional magazine feed type with double inclined grates the combination of a water leg, disposed on each side of a section, said legs extending to the top of said section and each provided with an inclined inner surface; a chamber in open communication with said water legs and extending across the top of said section; extensions of said chamber depending therebelow each inclined towards the inclined surface of a water leg; fuel magazines at the top of said section on opposite sides thereof, each magazine formed by a water leg, said chamber and an extension thereof, the inclined extension and the inclined surface of the water leg forming a constricted throat through which the fuel passes from the associated magazine; a water conduit in open communication with and connecting each depending extension with a water leg said conduit extending to a point near the grate, the upper surface of said conduit forming a flooring for some of the fuel in the magazine thereabove, said surface inclined to the horizontal to direct fuel therefrom to said constricted throat; and outlets from said water legs and from said chamber to an adjacent section.

8. In a heater construction of sectional magazine feed type with double inclined grates the combination of a water leg, disposed on each side of a section, said legs extending to the top of said section and each provided with an inclined inner surface; a grate support formed on said surface; a chamber in open communication with said water legs and extending across the top of said section; extensions of said chamber depending therebelow each inclined towards the inclined surface of a water leg to form therewith a constricted throat through which the fuel passes from a magazine therefor; a water conduit in open communication with and connecting each depending extension with a water leg said conduit extending to a point near the grate; means disposed at the bottom of said section between said water legs forming a second grate support; and outlets from said water legs and from said chamber to an adjacent section.

In testimony whereof I affix my signature.
JOSEPH A. WADDELL.
